Primary Examiner — Karen E Eldridge Powers

CLAIM

The ornamental design for a bra, as shown and described.

DESCRIPTION

FIG. 1 is a front, right and bottom perspective view of a bra showing my new design;

FIG. 2 is a rear, left and top perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is rear elevational view thereof showing how the bra may appear when worn.

The broken lines shown in FIG. 9 illustrate the arms, torso and neck of a person wearing the bra and form no part of the claimed design.
